UNITED STATES PATENT OFFICE.

GEORGE W. COX, JR., OF KENSINGTON, MARYLAND.

SORTING-MACHINE.

1,231,334.

Specification of Letters Patent. Patented June 26, 1917.

Application filed August 16, 1915. Serial No. 45,740.

To all whom it may concern:

Be it known that I, GEORGE W. Cox, Jr., a citizen of the United States, residing at Kensington, in the county of Montgomery 5 and State of Maryland, have invented certain new and useful Improvements in Sorting-Machines, of which the following is a specification.

This invention pertains to means for sorting papers, such as checks, sales slips, vouchers, and analogous articles, and it has for its objects among others to provide a simple and efficient machine for this purpose by means of which the checks, vouchers, or other papers or cards may be rapidly and accurately sorted by their serial numbers, symbols or other indicia or designating symbols.

It is a well known fact that in many 20 offices, for instance, where large numbers of checks, sales slips, or other papers designated by serial number, have to be sorted and arranged serially, much time and labor are required in this sorting. For instance, 25 in the office of the auditor for the Post Office Department, as well as the auditor for the Interior Department of the United States Government, and in many of the large departmental stores, thousands upon 30 thousands and hundreds of thousands of such papers have of necessity to be sorted and arranged according to their serial numbers. In departmental stores and other places the sales slips and papers of like 35 character are not only designated by serial number, but in many instances are further designated by class or book number and in such cases it is necessary to not only sort the sales slips or other papers according to 40 serial number, but the sales slips or other papers of each separate class or order. For instance, books numbered 1, 2, 3, etc., have to be separated in groups, that is, all of the sales slips or other papers of book 1, for 45 instance, must be sorted by themselves, and all the sales slips or other papers of, say, book 2 sorted by themselves, and so on.

My invention has for its objects broadly to provide a machine by which these various 50 sortings may be quickly and accurately accomplished, all by one and the same machine, by one and the same operator, the construction being such as to not require skilled labor in its manipulation.

It will thus be seen that the device now 55 to be described is particularly well adapted

for use in banks, railroad offices, departmental stores, in the offices of auditors, and in fact anywhere and everywhere that there is occasion to sort and classify papers of this 60 general character.

The invention in its broad sense contemplates various forms of devices for the accomplishment of the desired end, actuated by foot or hand power, electrically, or otherwise, as may be found most expedient and as may be found more desirable in accordance with the conditions under which it is to be operated. The machine may be equipped for operation on a large or small 70 scale to accommodate the various requirements and the necessities of the office in which it is to be used.

It combines the advantages of being accurate, rapid, simple in its structure, labor 75 saving, and economical in the consumption of power and space required. Furthermore, by the employment of my machine multiple handling of the papers is obviated. In hand sorting the papers all have to be handled a 80 multiplicity of times, three or more, the units in their pile, the tens in their pile, and the hundreds in their pile, and so on, and then these various piles again handled finally to place the papers all in their proper 85 arrangement from 1 up.

In some instances, it may be desirable to sort all of the vouchers, sales slips, or other papers, say of one department of a departmental store or the like by themselves, from 90 the others, without arranging such slips or the like according to serial number. This machine is equally well adapted for this purpose.

Other objects and advantages of the invention will hereinafter appear and the novel features thereof will be particularly pointed out in the appended claims.

The generic principle of the invention is capable of embodiment in a variety of 100 forms, some only of which are herein illustrated, those herein shown being what I at the present time consider preferable. It will be evident, however, that while the forms herein disclosed and now to be described are what I at the present time consider preferable, the same are subject to changes, variations and modifications in details, proportion of parts, relative arrangement, etc., and I, therefore, do not wish to 105 be restricted in the appended claims to the particular construction and arrangement of

parts, etc., as herein disclosed, but reserve the right to make such changes, variations, and modifications as come properly within the scope of the protection prayed.

5 The invention in its preferred forms is clearly illustrated in the accompanying drawings, which, with the numerals of reference marked thereon, form a part of this specification, and in which—

10 Fig. 1 is a plan view of a machine constructed in accordance with my present invention.

Fig. 2 is a side elevation thereof with parts in section.

15 Fig. 2^a is a perspective detail showing a foot operated form.

Fig. 3 is an enlarged vertical detail section as on the line 3—3 of Fig. 1, looking in the direction of the arrows.

20 Fig. 4 is an enlarged longitudinal section through one of the receivers removed.

Fig. 5 is an enlarged detail in elevation with portions in section, showing the clutch mechanism hereinafter more fully described.

25 Fig. 6 is a section on the line 6—6 of Fig. 5, looking in the direction of the arrows.

Fig. 7 is a top plan with a portion in section, of a portion of the receiver actuating mechanism.

30 Fig. 8 is a perspective detail on an enlarged scale of the receiver elevating rack.

Fig. 9 is a detail in side elevation with a portion in section, showing the movable pin 35 which limits the upward movement of the receiver.

Fig. 10 is a detail in elevation, with portions broken away and parts in section, of a portion of the receiver actuating and stop mechanism.

40 Fig. 11 is a plan view of one of the nests of keys.

Fig. 12 is a face view of a portion of the member with its openings for coöperation 45 with the pins that limit the upward vertical movement of the receiver.

Fig. 13 illustrates, diagrammatically, with portions in section, an electrically operated device of the general character herein-50 before referred to.

Like numerals of reference indicate like parts throughout the several views.

In carrying out my invention, I propose to make machines of varying capacities, 55 operable by any desired type of power, and it is to be understood that electrical means may be substituted for any or all of such actuating parts as are herein otherwise described. For instance, in the present in-60 stance, I have chosen to show oscillating receivers as adapted to be actuated by mechanical means, but it is evident that electrical devices may sometimes be employed for this purpose if found preferable. This 65 will, in a great measure, depend upon the

capacity of the machine, and such electrical devices may or may not be employed, as may be found most expedient. The following description as based upon the illustrations in the present drawings will be confined mostly to the particular construction of the different forms herein illustrated, but without any intent of limiting the invention to these particular forms further than the mechanism wherein resides the generic idea 75 soon to be made clear.

Referring to such drawings, 1 designates a base or support for the operating mechanism. This base may be of any required form and size dependent upon the character 80 of the machine to be supported thereupon.

This base 1 may support the motors 2 and 3, or in some instances a single motor may suffice if properly connected up, as will be apparent as the description proceeds. In 85 the present instance the motor 3 is shown as adapted to impart continuous rotary movement by means of the belt 4 to a feed roller 5, which with its coöperating feed roller 6 serves to feed the check, sales slip, or other 90 paper placed upon the supporting table 7 into the guide 8, by which it is directed into the proper compartment of the receiver, as will be made clear as the description proceeds.

95 The motor 2, by means of belt 9 which passes around a pulley 10 on a shaft 11, serves to impart rotary motion to the eccentric 12 on said shaft 11, which eccentric is designed, at predetermined periods, to bear 100 upon the upper face of the check, sales slip, or other paper upon the table 7, and force the same forward into the space between the feed rollers 5 and 6. The operation of the eccentric feed member 12 is so timed by 105 reason of the relative proportions of the pulley 10 and the pulley on the shaft 13 of the motor 2 as to give sufficient time for the receiver, soon to be described, to reach a proper position before the check, sales slip, 110 or other paper is fed forward.

On the shaft 13 of the motor 2 is a friction pulley 14 which imparts motion to a friction pulley 15 on a shaft 16, upon which latter shaft is a pulley 17 around which 115 passes a belt 18 which passes around a pulley 19 on a shaft 20 mounted in suitable bearings 21 and carrying a drum 22 on which is designed to be wound a cord, cable, or other ligament 23, which passes upward 120 over a pulley 24 mounted at the upper end of the upright 25 rising from the base, and over a pulley 26 on the outer end of an arm 27 supported from said upright 25, the end of said cord or ligament 23 being designed 125 to be connected with some suitable means, as shown at 28, on the cross bar 29 of the elevator rack 30 whereby the latter, with its appropriate receiver, may be elevated when required.

I may employ one, two, three, or more, receivers, according to the desired capacity of the machine and the purpose for which it is to be used. In small machines I may employ 5 receivers adapted for vertical movement only, dispensing with the oscillatory movement employed when a plurality of receivers are used. I will describe the machine as provided with a multiplicity of receivers and those mounted for vibratory as well as vertical movement, it being understood that when it is desired to give only vertical movement to the receiver the mechanism by which the receivers are oscillated 10 may be dispensed with.

In the present instance, the receivers are shown as ten in number, and for the sake of convenience, I have designated these receivers as *a*, *b*, *c*, *d*, *e*, *f*, *g*, *h*, *i* and *j*. Each 15 receiver may be made of any required height or capacity, dependent upon the character of sorting to be done. If the papers are to be sorted merely into groups, each receiver will have a less number of compartments 20 and each compartment of greater capacity. When checks and such papers are to be sorted according to serial number, each receiver will have, say, 1,000 compartments, each compartment, as will be readily understood, being designed to receive one check. 25 In Fig. 2 I have broken away the side wall of one of these receivers to show its compartments, but in this view the height of each compartment is greatly exaggerated for the purpose of illustration. The compartments (in the present instance horizontally disposed) are formed by suitable shelves or partitions 31, as will be readily understood upon reference to Fig. 2 and also to Fig. 3, 30 in which parts are shown further enlarged. Each compartment is designed to receive its particular check as it is guided thereinto through the guide 8, as will be evident upon reference to Fig. 3. In order that the 35 checks, sales slips or other papers may not be thrown outward as the receivers are moved, the shelves or bottoms of each compartment are inclined from the front rearward, as shown clearly in Fig. 2. This inclination further assists in the checks, sales slips or other papers being deposited into the rear portion of the compartments as they are fed thereinto through the guide 8 by the feed mechanism above described. Each 40 shelf or partition 31 is, by preference, cut away at one end, as seen at 32 in Fig. 4, to admit of easy removal of the checks or other papers after they have been sorted into their various compartments.

When a plurality of receivers are employed, as shown in Fig. 1, they are arranged upon the arc of a circle and mounted to move in unison in a horizontal plane, and each receiver also adapted to be moved vertically independently of the others. In the

present instance I have chosen to show these receivers as supported in the following manner:—33 is a transverse member which supports the arc-shaped member 34, from which rise a plurality of guiding members 35 in which each receiver is guided in its vertical movements in any suitable manner, as, for instance, by guide pins 36, as seen best in Fig. 1. The member 33 is suitably braced by the angularly disposed member 37, see 70 Fig. 1, which extends to the vertical shaft 38, about which the oscillating frame and the plurality of receivers oscillate in a manner soon to be described.

Fast to the shaft 38 is a member 39 having two arms 40 and 41, the former having a recess or the like 42, and the latter a similar recess 43, as seen clearly in Figs. 1 and 7.

44 is a transversely disposed rock shaft mounted in suitable bearings 45, as seen in Fig. 7, and rigid with this rock shaft upon opposite sides of its longitudinal center are the rocker arms 46 and 47, see Figs. 1, 2 and 7. These rocker arms carry at their free ends the upwardly extending pins 48 and 49, as seen in Figs. 1, 2 and 7, which are designed to engage in the recesses 42 and 43 of the arms 40 and 41 on the shaft 38 to rock the same and, consequently, oscillate the receivers.

Secured to the ends of the rock shaft 44 are the curved members 50 and 51, seen best in Figs. 1, 2 and 7, for a purpose which will hereinafter appear.

52 is a supporting member extending concentric with the members 50 and 51 just described, as seen in Figs. 1 and 2. This member 52 may be supported in any suitable manner, as, for instance, by uprights or posts 53, one of which is seen in Fig. 2. It 100 may further be braced by a bar 54 extending radially from the shaft 25, as seen in Fig. 2, and this member 54 is provided with an upwardly extending notch or the like 55, seen also in Fig. 2, to permit of the necessary upward movement of the members 50 and 51.

As seen in Figs. 1 and 2, I employ a plurality of master keys and for convenience in readily distinguishing the same as noted in the description of the operation of the device, I have designated these keys as *a**, *b**, *c**, *d**, *e**, *f**, *g**, *h**, *i** and *j**, as seen in Fig. 1. Actuation of these master keys controls the limit of movement of the receivers *a* to *j*. Each master key has its stem 56 mounted for vertical reciprocation through an opening in the table or the like 57, see Fig. 2, and each master key is designed to bear upon and serve to depress a key lever 58, see Figs. 1, 2 and 10. Each key lever 58 is fulcrumed upon a suitable fulcrum, as 59, which, as will be seen best from Fig. 10, is, by preference, a knife bearing for an obvious purpose. The other end of each key lever 58 125

engages beneath one or the other of the members 50 or 51, see Figs. 1 and 2, and intermediate its fulcrum and the point of contact of the inner end of said lever 58 with the member 50 or 51, the lever 58 carries an upright pin 60 movable through an opening in the member 52, as seen best in Fig. 10, and its upper end 61 movable through an opening in the member 34. A spring 62 around the pin 60 between the members 34 and 52 and rendered adjustable by means of a nut 63 on said pin to vary the tension of the spring, serves to normally keep the inner end of the lever 58 down and, consequently, the master key in its uppermost position. It is to be understood that there are as many of these pins as there are master keys or receivers *a*, *b* etc., and these pins are to determine the amount of throw or movement of the receivers to the right or the left. 64 is a pin or member extending from the center of the space between the receivers *e* and *f*, as seen in Fig. 1, which pin or member 64 is designed to contact with the upwardly projected pin of the appropriate lever 58 to limit the movement of the carrier by which the different receivers are supported and with which they move. 65 and 66 are springs attached to opposite ends of the oscillatory carrier, as seen in Fig. 1, for returning the same to its normal or central position after the checks or other papers have been deposited within the receiver which has been moved in proper relation to the feeding device hereinbefore described and received its appropriate number of slips or checks or other papers. 67 is a spring for normally keeping the members 50 and 51 in their lowermost position. Although but one spring is seen in the drawing and that in Fig. 2, it is to be understood that there is a spring for each of the members 50 and 51. On the shaft 20 is a fixed member 68 of a clutch and slidably mounted on said shaft is the movable member 69 of said clutch, as seen clearly in Figs. 1 and 5. Around the shaft between these two clutch members is a spring 70 tending to normally keep the clutch members separated. Between the hub 71 of the pulley 19 and the adjacent end of the clutch member 69 is an annular groove 72 in which are arranged the oppositely disposed pins 73 and 74 which join the adjacent and overlapped ends of the links 75 and 76, as seen in Figs. 5 and 6. These links at their lower ends are pivotally connected, as at 77, with the laterally projecting lug or support 78 carried by the post or standard 79, as seen in Fig. 2. The upper ends of the links 75 are connected by the cross bar 80, as seen in Fig. 6, to which is pivotally or loosely connected, as at 81, one end of a bar 82, see Figs. 5 and 6, each bar tending downwardly in an inclined direc-

tion, as seen in Fig. 2, and near its front end is pivotally mounted, as at 83, on the post or standard 84 rising from the base 1. The bar 82 extends beyond its pivot, as seen in Fig. 2, and terminates in an upward extension 83^x, seen best in Fig. 2, and upon this upward extension bears a lever 84^x, there being a lever for each of the keys—not the master keys—but keys which determine the vertical movement of the receivers now to be described. These keys are arranged in groups, as seen in Fig. 11, the keys of each group being numbered from 1 to 99, and, as seen in Fig. 1, there are ten of these groups. These keys 85 are each depressible independently of the other and each key with its member 84^x is kept in its elevated position by means of a spring 86, one attached to each member 84^x and to the base-member 1, as seen best in Fig. 2. Each of these members 84^x is pivotally mounted, as at 87, see Figs. 2 and 9, and rigid therewith is a vertical member 88, the upper end of which is pivotally connected, as at 89, with a horizontally projectable pin 90, each pin being movable through its appropriate hole 91 in a plate or member 92, as seen in Fig. 9. These upright members 88 and their pins 90 are preferably inclosed within a suitable casing 93, as seen in Figs. 1 and 2. The holes 91 are arranged in rows slightly inclined from the horizontal, as seen in Fig. 12, for an obvious purpose.

Referring to Fig. 2, 94 is a suitable source of electricity, from which extend the wires 95 and 96 which, in turn, are connected with the plates 98 and 97 respectively. Carried by the levers 84^x are contact points 99 and 100, as seen in Fig. 2, for co-operation with said plates 98 and 97, as will be hereinafter set forth. The wire 95 connects through the motor 2 and the wire 101 with the said plate 97, as seen in Fig. 2.

In some instances, as hereinbefore suggested, I may construct a machine in which the receivers *a*, *b*, etc., will be given vertical movement only, as, for instance, in a machine requiring but one receiver, or possibly more, and instead of giving vertical movement to this receiver by the means hereinbefore described, I may employ a foot-operated pedal 102, as seen in Fig. 2^a, pivotally connected, as at 103, with the lower end of the cord or other actuating member 23, so that by depression of the foot pedal 102 which is fulcrumed at 104 on some suitable support, as 105, the cord or ligament 23 will be pulled downward and the receiver raised. The receiver is designed to be returned to its normal position by gravity.

With the parts constructed and arranged substantially as hereinbefore described and as illustrated in the drawings, the operation, briefly described, is as follows:

Assuming first that the device embodies

but one receiver, as *f*, see Fig. 2, and this designed to be given merely vertical movement, which movement may be given thereto by foot or other power, and this receiver provided with the requisite number of compartments, and the machine equipped with as many keys, 85, as there are compartments in the receiver, the master keys *f*, etc., not being required, the checks or other papers 10 are placed upon the table or support 7 ready to be fed to the machine. The operator looks at the number of the check, sales slip, or other paper, and supposing it, for instance, to be No. 2, he depresses the key, 85, of the 15 first bank or group of keys bearing the numeral 2. The depression of this key depresses the corresponding lever 84 and by actuation of the member 88 throws the pin 90 corresponding to said key 2 through the 20 proper opening 91 in the plate or member 92 and into the path of the receiver. This pin serves to limit the upward movement of the receiver at the proper point to bring compartment 2 in proper position to receive 25 the check or other paper as it is fed thereto by the cam member 12 and the feed rolls 5 and 6 and the guide 8. The receiver may be caused to move upward until it is stopped by its projecting pin in a variety of ways. 30 In the single machine where the receiver has vertical movement only, a very convenient way of raising the receiver is by means of the foot pedal 102 shown in Fig. 2^a. The depression of this foot pedal pulls downward upon the ligament 23 connected with the end of said foot pedal and, consequently, pulls up on the other end of said ligament bringing the receiver up to the point where it is stopped by the projecting pin. The 35 receiver, in this instance, may be elevated in any suitable way, as by the elevating cage 30, shown, or by attachment of the ligament 23 directly to the receiver. The receiver, being elevated to the proper position, the 40 top check or other paper is fed by any suitable means, automatic or hand, onto the table 7, where it is engaged by the cam member 12 which, as hereinbefore described, is properly timed, and thereby fed to and 45 between the feed rollers 5 and 6 which are constantly revolving by connection with the motor hereinbefore described, and after passing between the feed rollers the check is guided through the guide 8 into the compartment 2 of the receiver. As soon as the 50 check or other paper is fed into its proper compartment, pressure on the key is removed and the lever 84 is returned to its normal position upward by means of its 55 spring 86 and this movement, consequently, withdraws the pin 90 inward out of the path of the receiver, which latter, by reason of the removal of the pressure upon the foot pedal, falls by gravity to its normal or lowest 60 position. It will be noted, however,

that if the next paper to be fed is to be fed to a compartment of the receiver necessitating that the latter be elevated to a greater height, the pressure upon the foot pedal 102 need not be removed but by continued pressure the receiver is moved upward until it strikes the next projected pin 90, where the receiver stops, and the motions just described are repeated, the check being fed into its proper compartment. 70

The requisite motions may be given to the receiver by electrically-operated or other means in lieu of the foot pedal and connections just described. 75

Now, supposing the next check or paper bore the number 102, the operation will be identically the same, except that the operator depresses the key 2 in the second group or nest of keys which will actuate the proper pin so as to stop the receiver in its vertical movement at a point where the check will be fed into compartment 102 thereof, and so on. If the check bear the number 902, the operator has simply to depress the key No. 2 in the ninth group or nest of keys and the check or other paper will be fed into compartment 902 of the receiver, which latter has been raised to such position as to be stopped by its appropriate pin. From this it will be seen that the machine is positive and accurate in its functions and that if the appropriate key is depressed the check or other paper cannot fail to be delivered into the appropriate compartment of the receiver. 85

The checks or other papers may be removed from the compartment of the receiver in any suitable manner. 90

More than one paper may be fed to any one of the compartments, if desired, it being understood that the capacity of the compartments may be varied with the character of the sorting to be done. For instance, any one or more of the receivers may have its partitions or shelves removable for this purpose, 1, 2, or more shelves being removed to give the required capacity to the compartment. When it is remembered that with ordinary bank checks and analogous papers, the paper is practically about 1/250 of an 110 inch in thickness, it will be seen that one receiver can be provided with a numerous number of compartments and still not be unprohibitive in its height, and by making the receivers of exceedingly thin aluminum or 115 other light material the weight thereof will be but very little. 120

Where more than one paper is to be fed to the one compartment, any suitable means may be employed at the receiving points to 125 press down the front ends of the papers already in the box so as to facilitate the entrance of the additional paper. All of these expedients are well known and could be readily applied to my device either when it is 130

originally constructed or after it has been in use, should such accessory be found desirable.

While in the foregoing description I have referred to the stop members 90 as being laterally projected pins, it is to be understood that in the appended claims where I refer to stop members or the like I do not intend to restrict myself to this particular form of stop members, that is, the horizontal projecting pins, as pivoted means or means moving in the arc of a circle, or any other mechanical equivalents may be substituted for such pins 90 without in any way changing the character of the machine or the mode of operation or the function of such stop members.

Having now described the operation of the machine with the single receiver and that adapted only for vertical movement, I will now describe the operation of a machine embodying a plurality of receivers and those mounted for oscillatory movement in a horizontal plane, such machine being shown in Figs. 1 and 2 and the details thereof being shown in the other views with the exception of Fig. 2^a, although it is to be understood that the cross sectional view, Fig. 4, pertains to a receiver no matter in which form of machine it may be employed, whether the receivers reciprocate in a straight line or are oscillated, and that the group or nest of keys seen in Fig. 11 and the member 92 seen in Fig. 12 with its holes 91 are common to all of the different forms of the machine.

Assuming that the parts seen in Fig. 1 are in normal position, the mode of operation is as follows: The operator observes the number of the check to be first fed to the machine, and supposing said check to bear the number 2 the master key is first depressed. The depression of this key depresses the outer end of the corresponding member 58 which, in turn, raises the member 51 and thus through the rock shaft 44 causes the member 47 to be thrown in the direction of the arrow in Fig. 1 so that its pin 49 will engage in the recess 43 of the rocking member 41 and rock the latter so as to throw the receivers as a whole in the direction of the arrow *a* in Fig. 1. This movement continues until the member 64 engages with the pin 60 which has been previously projected. This brings the proper receiver, in this instance the receiver *j*, into central position and upon the bottom members of the elevating rack 30. When the receiver has reached the proper position, the operator presses upon the proper key 85 which depresses the appropriate member 84^x, bringing the contacts 99 and 100 into operative contact with the plates 98 and 97, as will be readily understood upon reference to Fig. 2, thus starting the motor 2, it being understood that the motor 3 is, by prefer-

ence, in operation at all times. When the motor 2 is started, it imparts motion to the eccentric wiper or member 12 and also by depression of the upwardly extending portion 83^x of the member 82 (which, as will be understood upon reference to Fig. 2, is designed to be depressed by the operation of any one of the keys by means of the transverse member 106, which is common to all of said keys, as seen clearly in Fig. 1) it elevates the other end of said member 82, thus straightening out the toggles 75 and 76, moving the clutch member 69 into engagement with the clutch member 68 on the shaft 20, and when these clutch members are thrown into operative engagement the shaft 20 will be revolved by means of the belt 18 on the pulley 19 on said shaft 20, as seen in Figs. 1 and 2, and the drum 22 is revolved, winding up the ligament 23 thereupon until the receiver which has been engaged by the elevating rack 30 reaches such height as to engage the appropriate pin 90 which has been thrown out into the path of said receiver by the depression of the unit key 90 through the medium of the member 88 in the same manner as above described in connection with the simplest form of the invention. The check or other paper is now fed in and carried along by the eccentric member 12 through the rollers 5 and 6 and through the guide 8 into the appropriate compartment of the receiver which is determined by the height of such receiver. The pressure on the keys is then removed when the parts are returned to their normal position by reason of the springs 86 acting on the members 84^x, the springs 67 acting on the members 50 and 51 and the springs 62 on the pins 60, gravity returning the receiver to its normal lowermost position. The pin 90 is at the same time withdrawn so as not to project in the path of the receiver in its next movement, which latter is determined by the pin which is projected by the depression of the next unit key. The receivers are returned to their normal position laterally by means of the springs 65 and 66.

Now assuming that the master key 10 is depressed, the member 50 will be raised by the engagement of the appropriate member 58 therewith and the elevation of this member 50 rocks the shaft 44, moving the vertical member 107 in the direction of the arrow seen in Fig. 2, consequently moving the arm 46 in the direction of the arrow shown in connection therewith in Fig. 2 until its pin 48 engages in the recess 42 of the arm 40 of the oscillating member 39 which is rocked to throw the receivers in the direction of the arrow *b* seen in Fig. 1 until the member 64 engages with the pin 60 at the upper end of Fig. 1, when receiver *a* will be brought into the central position to be engaged by the elevating rack 30 and moved

to its appropriate height, governed by the position of the pin 90 which is projected by the depression of the appropriate unit key.

Actuation of the appropriate master key 5 projects the proper pin 60 to limit the oscillatory movement of the carrier so that the receiver corresponding to the master key operated will be sure to be brought into central position in proper position for elevation by the elevating rack 30.

When the member 84^a is raised to its normal position, pressure on the member 106 is removed so that the long arm of the member 82 returns to its normal position, 15 and the toggles 75 and 76 are thrown into their normal position, that seen in Fig. 5, separating the clutch members, leaving the drum 22 in position to revolve freely, permitting the receiver to fall by gravity to its 20 lowermost position.

Any suitable means may be provided to prevent the checks or other papers from falling out at the rear of the receivers. For instance, a vertical pin as a' seen in Figs. 1 25 and 4, may be provided, dropped vertically through an opening in the top of the receiver and readily removed when it is desired to remove the papers from the compartments of the receiver.

30 In Fig. 13 I have illustrated diagrammatically means for electrically performing the operations hereinbefore described in connection with Figs. 1 and 2.

In said Fig. 13, 5^a and 6^a are the feed 35 rollers, 8^a is the guide, 4^a is the belt for operating the feed rollers, 9^a is the belt for operating the eccentric member 12^a on the shaft 11^a which also carries the belt pulley 10^a.

40 23^a is the ligament for hoisting the elevator rack 30^a and the receivers; 22^a is the drum on which the ligament 23^a is wound.

90^a designates one of the pins which in the present instance is in the form of a 45 solenoid, 92^a being the equivalent of the plate or member 92 seen in Figs. 1 and 2, and this plate is composed preferably of an inner and outer metallic member 92^b and 92^c and an intermediate insulating plate 92^d, 50 there being co-incident holes through the three plates for the reception and guidance of the pins 90^a.

108 is a reversible motor designed to give the back and forth oscillatory movement to 55 the carrier and the receivers. 60^a is the pin, equivalent to the pin 60 in the forms above described, designed to limit the oscillatory movement of the carrier and to stop the appropriate receiver in the appropriate 60 position to be raised by the elevator rack.

109 designates one of the master keys and 110 one of the unit keys, while 111 is a switch. 112 is a contact point to complete the circuit by depression of the master key 65 while 113 is a similar contact point for com-

pleting the circuit by depression of a unit key 110.

In operation, the steps and results are the same as when manipulated in the manner hereinbefore described in connection with 70 Figs. 1 and 2. Briefly stated, it is as follows:

When the master key 109 is depressed, its contact with the contact point 112 completes the circuit and the appropriate pin 60^a is 75 raised to form a stop for the movement of the carrier on which the receivers are mounted and the motor 108 is actuated to move the carrier to the right or left in accordance with the depression of the master key. Now the appropriate unit key is depressed until it contacts with the contact pin 113, completing the circuit, when the appropriate solenoid will be actuated to project its pin through the opening in the plate 92^a in 80 position to stop the vertical movement of the appropriate receiver, which vertical movement is now given to such receiver by actuation of the drum 22^a and when the receiver is brought to its proper vertical position the check is fed into the appropriate compartment thereof in the same manner as above described in connection with the construction shown in Figs. 1 and 2. It is to be understood that the drum is put in 85 motion by completion of the circuit when the pin 90^a contacts with the outer plate 91^a of the plate 92^a.

What is claimed as new is:—

1. In a sorting machine, a vertically bodily movable receiver having a multiplicity of compartments, selective mechanism controlling said receiver, means for elevating said receiver coöperating with said selective means, means operable with said selective mechanism for limiting the movement of said receiver, and presenting a selected compartment in operative relation to a feeding station.

2. In a sorting machine, a vertically bodily movable receiver having a multiplicity of compartments, means for elevating the same, selective means coöperating with and controlling said elevating means, and means coöperable with the selective means and projectable into the path of the receiver and limiting its bodily movement.

3. In a sorting machine, a vertically bodily movable receiver having a plurality of compartments the walls of which are inclined 120 downwardly from front to rear, means for elevating said receiver, selective means coöperating with and controlling said elevating means, and means coöperating with the selective means and projectable into the path 125 of the receiver and limiting its bodily movement.

4. In a sorting machine, a vertically bodily movable receiver having a plurality of compartments the walls of which are inclined 130

- downwardly from front to rear, means for elevating said receiver, selective means co-operating with and controlling said elevating means, means coöperating with the selective means and projectable into the path of the receiver and limiting its bodily movement, and means for preventing a displacement of the articles received within said compartments.
- 5 10. 5. In a sorting machine, a vertically bodily movable receiver having a plurality of compartments the walls of which are inclined downwardly from front to rear, means for elevating said receiver, selective means co-operating with and controlling said elevating means, means coöperating with the selective means and projectable into the path of the receiver and limiting its bodily movement, and means for feeding papers one by one to the selected compartment.
- 15 6. In a sorting machine, a bodily movably mounted receiver having a multiplicity of compartments, a nest of keys, selective mechanism controlled by said keys, means actuated by the depression of the keys to limit the movement of said receiver, and means for feeding papers one by one to the selected compartment.
- 20 7. In a sorting machine, a bodily movably mounted receiver having a multiplicity of compartments, feeding means to feed papers one by one to a selected compartment, a nest of keys and means operable by the depression of a key to bring a selected compartment into coöperative relation with said feeding means, and means actuated by the depression of said keys and movable into the path of the receiver to limit its movement.
- 25 8. In a sorting machine, a bodily movably mounted receiver, a nest of keys, means operable by the depression of a key to move said receiver, means operable by the depression of a key to bring a selected compartment of said receiver into predetermined position, means operable with said selected means and movable into the path of the receiver to limit its movement, and means for returning said key and withdrawing the said limiting means.
- 30 9. In a sorting machine, a bodily vertically movable receiver, depressible key-operating means for elevating the same and bringing a selected compartment into predetermined position, a key-operated member and compartment-selecting means controlled thereby for projecting a member into the path of the receiver to limit its upward movement, and means for feeding articles to the selected compartment one by one.
- 35 10. In a sorting machine, a bodily vertically movable receiver, depressible key-operated means for elevating the same, a key-operated member, compartment-selecting means controlled thereby for projecting a
- member into the path of the receiver to limit its upward movement and means for giving the receiver movement in a horizontal plane and means for feeding a paper to the receiver when it has reached its predetermined position.
- 40 11. In a sorting machine, a bodily vertically movable receiver, a depressible compartment-selecting key, means actuated by said key to determine the amount of movement of the receiver, means actuated by said key for elevating the receiver, and means for feeding articles to said receiver when it reaches its predetermined position.
- 45 12. In a sorting machine, a bodily vertically movable receiver, a depressible key, means actuated by said key to determine the amount of movement of the receiver, means actuated by said key for elevating the receiver to bring a selected compartment into predetermined position, a feeding device, and means for actuating the latter by the depression of the key.
- 50 13. In a sorting machine, a vertically movable receiver, a depressible key, means actuated by said key to determine the amount of movement of the receiver, means for elevating the receiver to bring a selected compartment into predetermined position, a feeding device for feeding articles one by one to a selected compartment, means for actuating the latter by the depression of the key, and means for oscillating the receiver in a horizontal plane.
- 55 14. In a sorting machine, a bodily vertically movable receiver, means connected therewith for elevating the same, a depressible key controlling said means, a projectable member actuated by the key to limit the movement of the receiver to bring a selected compartment into predetermined position, and means for giving movement in a horizontal plane to said receiver and means for feeding a paper to the receiver when it has reached its predetermined position.
- 60 15. In a sorting machine, a bodily vertically movable receiver, means connected therewith for elevating the same, a depressible key controlling said means, a projectable member actuated by the key to limit the movement of the receiver to bring a selected compartment into predetermined position, means for giving movement in a horizontal plane to said receiver, and a feeding device operable by the depression of the key to feed articles one by one to a selected compartment.
- 65 16. In a sorting machine, positive feeding means and a receiver having a multiplicity of compartments and mounted for bodily horizontal movement and for bodily vertical movement to bring only a selected one of said multiplicity of compartments into predetermined position with relation to said feeding means.

17. In a sorting machine, positive feeding means and a receiver having a multiplicity of compartments and mounted for bodily oscillatory movement and for bodily vertical movement to bring only a selected one of said multiplicity of compartments into predetermined position with relation to said feeding means. 70
18. In a sorting machine, a bodily movable receiver mounted for horizontal oscillatory movement, means controlled by the depression of a key for giving oscillatory movement to said receiver, and means controlled by the depression of the key to elevate said receiver to bring a selected compartment thereof into predetermined vertical position. 75
19. In a sorting machine, a receiver mounted for oscillatory movement, means controlled by the depression of a key to determine the amount of movement of said receiver, said receiver being mounted also for vertical movement. 80
20. In a sorting machine, a receiver mounted for oscillatory movement, means controlled by the depression of a key to determine the amount of movement of said receiver, said receiver being mounted also for vertical movement, and means actuated by the depression of a key to determine the vertical movement of said receiver. 85
21. In a sorting machine, a plurality of receivers connected together for simultaneous movement and each having a plurality of compartments and mounted for oscillatory movement, and means for elevating any one of said receivers independently of the others to bring a single selected compartment of said receiver into predetermined position. 90
22. In a sorting machine, a multiplicity of receivers connected together for simultaneous movement and each having a plurality of compartments, means for moving all of said receivers simultaneously in a horizontal plane, and means for bodily moving any one of said receivers vertically to bring a single selected compartment thereof into predetermined position. 100
23. In a sorting machine, a multiplicity of receivers connected together for simultaneous movement and each having a plurality of compartments, means for moving them simultaneously in a horizontal plane, means for moving a selected receiver vertically to bring a single selected compartment thereof into predetermined position, and means for determining the amount of movement thereof. 105
24. In a sorting machine, a multiplicity of receivers connected together for simultaneous movement and each having a plurality of compartments, means for moving said receivers simultaneously in a horizontal plane, means for automatically determining the amount of movement thereof, and elevating means for moving any one of said receivers bodily vertically independently of the others to bring a single selected compartment thereof into predetermined position. 110
25. In a sorting machine, a multiplicity of receivers each having a plurality of compartments, means for giving them oscillatory movement in unison, means for automatically determining the oscillatory movement, means for elevating any one of said receivers bodily independently of the others to bring a single selected compartment thereof into predetermined position, and means for determining the amount of vertical movement of such receiver. 115
26. In a sorting machine, a multiplicity of receivers, means for moving them in a horizontal plane, key-controlled means for limiting the horizontal movement of said receivers, and key-controlled means for limiting the vertical movement of any one of said receivers. 120
27. In a sorting machine, a multiplicity of receivers, means for moving them in a horizontal plane, key-controlled means for limiting the horizontal movement of said receivers, key-controlled means for limiting the vertical movement of any one of said receivers, and means for elevating the selected receiver. 125
28. In a sorting machine, a plurality of receivers movable together in horizontal planes and singly in vertical planes and each having a plurality of compartments, positive feeding means, and selecting mechanism for bringing the desired receiver into position for any one selected compartment only thereof to present said one compartment only to the feeding means to receive a check. 130
29. In a sorting machine, a plurality of receivers movable together in a horizontal plane, selecting mechanism for bringing the desired receiver into position to receive a check, and means for elevating the selected receiver. 135
30. In a sorting machine, a plurality of receivers movable together in a horizontal plane, selecting mechanism for bringing the desired receiver into position to receive a check, means for elevating the selected receiver, and key-controlled means for determining the vertical movement of said receiver. 140
31. In a sorting machine, a multiplicity of receivers, means for giving them oscillatory movement in a horizontal plane, selective mechanism for bringing the desired receiver into position to receive a check, said receivers being movable vertically, and key-operated means for elevating the selected receiver. 145
32. In a sorting machine, a multiplicity of receivers, means for giving them oscillatory movement in a horizontal plane, selective mechanism for bringing the desired receiver into position to receive a check, said receivers being movable vertically, and key-operated means for elevating the selected receiver. 150

latory movement in a horizontal plane, selective mechanism for bringing the desired receiver into position to receive a check, said receivers being movable vertically, key-
5 operated means for elevating the selected receiver, and key-operated means for determining the vertical movement of such receiver.

33. In a sorting machine, a multiplicity
10 of receivers each having a multiplicity of compartments and bodily movable together in a horizontal plane, selective mechanism therefor, means for bodily elevating the selected receiver to bring a single selected
15 compartment thereof into predetermined position, and a coöperative feed device to feed articles to such single selected compartment one by one.

34. In a sorting machine, a multiplicity
20 of receivers each having a multiplicity of compartments and bodily movable together in a horizontal plane, selective mechanism therefor, means for bodily elevating the selected receiver to bring a single selected
25 compartment thereof into predetermined position, a coöperative feed device to feed articles to such single selected compartment one by one, and means for automatically determining the amount of movement of the
30 receiver in a vertical direction.

35. In a sorting machine, a multiplicity of receivers, means for oscillating them together in a horizontal plane, selective mechanism, a coöperative feed mechanism, and
35 key-controlled means for raising the selected receiver.

36. In a sorting machine, a multiplicity of receivers, means for oscillating them together in a horizontal plane, selective mechanism,
40 a coöperative feed mechanism, key-controlled means for raising the selected receiver, and key-controlled means for limiting the vertical movement of the receiver.

37. In a sorting machine, a plurality of
45 receivers, means for oscillating them in a horizontal plane, selective mechanism, key-

controlled elevating mechanism for the selected receiver, key-controlled projectable means for limiting the vertical movement of the selected receiver, and means for feeding 50 a paper to the selected receiver.

38. In a sorting machine, a plurality of receivers mounted for oscillatory movement in a horizontal plane and for independent vertical movement, a master key and connections for selecting any desired receiver and means for elevating such selected receiver. 55

39. In a sorting machine, a plurality of receivers mounted for oscillatory movement 60 in a horizontal plane and for independent vertical movement, a master key, connections for selecting any desired receiver and means for elevating such selected receiver, and means for determining the vertical 65 movement of said receiver.

40. In a sorting machine, a plurality of receivers mounted for oscillatory movement in a horizontal plane and for independent vertical movement, a master key and connections for selecting any desired receiver, 70 means for elevating such selected receiver, means for determining the vertical movement of said receiver, and key-controlled means for said elevating means. 75

41. In a sorting machine, a plurality of receivers each with a multiplicity of compartments, said receivers being mounted for horizontal movement in unison and any one of said receivers mounted for independent 80 bodily vertical movement, means for moving said receivers horizontally and determining the amount of movement thereof, and means coöperating therewith to give vertical movement to a selected receiver and to limit its 85 vertical movement.

In testimony whereof I affix my signature in presence of two witnesses.
